Primary Examiner — Catherine Tuttle(74) *Attorney, Agent, or Firm* — Haynes and Boone, LLP(57) **CLAIM**

The ornamental design for an LED ball, as shown and described.

DESCRIPTION

FIG. 1 is a top and front perspective view of the LED ball showing my new design;

FIG. 2 is a rear and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawings are included for the purpose of illustrating portions of the LED ball that form no part of the claimed design.
